Harold E. Stonebraker,
his ATTORNEY

UNITED STATES PATENT OFFICE.

FRANK A. ADAMS, OF ROCHESTER, NEW YORK, ASSIGNOR TO BURT C. OLNEY, OF ROME, NEW YORK, AND FLORENCE C. DAILEY, OF ROCHESTER, NEW YORK.

CLOTHES-WASHING MACHINE.

1,406,137.

Specification of Letters Patent. Patented Feb. 7, 1922.

Application filed May 21, 1921. Serial No. 471,321.

To all whom it may concern:

Be it known that I, FRANK A. ADAMS, a citizen of the United States of America, and residing at Rochester, in the county of Monroe and State of New York, have invented certain new and useful Improvements in Clothes-Washing Machines, of which the following is a specification.

My invention relates to agitating machines particularly adapted for washing clothes or the like, and is in the nature of an improvement of the construction embodied in my application filed April 21, 1921, Serial No. 463,176.

One of the principal objects of the present improvement is to afford means for insulating the hydraulic motor from the water within the washing receptacle so that the hot water within the receptacle will not be cooled by the cold water of the motor.

Another object of the invention is to afford a simple, practical and efficient mechanism for effecting the intermittent rotary motion of the carrier on which the agitating cups are mounted.

The invention also includes certain other improved features, all of which will appear clearly from the following description in conjunction with the accompanying drawings, the novel features being pointed out in the claims following the description.

In the drawings:

Figure 1 is a vertical sectional view of a machine constructed in accordance with a preferred embodiment of the invention.

Figure 2 is an enlarged sectional view of the valve mechanism.

Figure 3 is an enlarged side elevation of the parts by which the intermittent rotary motion of the carrier is effected.

Figure 4 is a sectional view on line 4—4 of Figure 3.

Figure 5 is an enlarged sectional view on line 5—5 of Figure 1, and

Figure 6 is a perspective view of one of the legs.

1 designates the clothes receptacle, in which the hot water and soiled clothes are placed, and arranged therein for vertical reciprocatory motion are the agitating devices, preferably in the form of cups 2, mounted upon the carrier or vertical piston rod 3. The latter carries at its lower end a piston 4 which travels in a cylinder 5. The

cylinder 5 is surrounded by a housing 6, to permit water to pass from the port 7 upwardly, between cylinder 5 and housing 6 so as to reach the upper end of the cylinder and actuate the piston downwardly, and during the upward stroke of the piston, water enters at the lower end of the cylinder 5, passing directly from the valve housing 8.

The parts thus far described are the same as in my application above mentioned. The hydraulic motor is operated by cold water, usually by connection with an ordinary faucet and it is essential that the hot water in the receptacle maintain its heat as long as possible, and therefore that it should not come in direct contact with the hydraulic motor. To this end, I have provided a jacket 9 surrounding the motor and in spaced relation thereto so as to afford an annular space 10. The jacket 9 is fixedly attached to the nut 11 and communicates at its lower end with an opening 12 extending through said nut and through the bottom of receptacle 1. The jacket 9 is also provided with a slight opening 12 at the top through which air can pass, thus affording a continuous circulation between the jacket 9 and the motor. The air passing between these walls dissipates the cold emanating from the motor and affords an effective insulation, so that the temperature of the water in the receptacle 1 is not reduced to any substantial extent.

In order to effect the necessary intermittent rotary motion of the carrier 3, there is provided the sleeve 13, with annular slot 14 engaging a fixed pin 15 as in my prior application. The sleeve 13 of the present embodiment differs from the previous construction in that it is formed at the bottom with an enlarged base or plate 16, provided on its bottom with a frictional surface, preferably in the form of radial corrugations. The piston 4 is also provided on its upper surface with similar radial corrugations, and arranged between the piston 4 and the bottom 16 of the sleeve, is a frictional washer 17, preferably formed of leather, or of other similar material.

As the piston 4 travels upwardly, it engages and compresses the washer 17 against the bottom 16 of the sleeve with sufficient friction so that as the sleeve is rotated, it causes a corresponding rotary travel of the piston and carrier 3, and also of the agitat-

ing cups, and on the downward motion of the piston, the sleeve 13 returns to its initial position without causing any return travel of the carrier 3. A primary advantage of this arrangement is that in case the clothes within the receptacle become wrapped around the carrier 3, or otherwise entangled, such resistance will overcome the pressure of the friction clutch just described, with the result that the carrier and the agitating cups will not be rotated, although the motor may continue in operation. This will prevent damaging the clothes and give the operator an opportunity to stop the machine, and properly arrange the clothes in the receptacle before proceeding further.

The motor is controlled by valves mounted on valve rod 18, as described in my previous application, and connected to said valve rod 18 is a bell crank 19 pivoted at 20. The arm 21 of the bell crank is connected to a plate 22 which is fixed on the rod 23 connected to the piston 4. Also connected to the arm 21 of the bell crank is a link 25, which carries a yoke 26 cooperating with the pin 27. The link 25 is pivotally mounted in a plunger 28 which is actuated by a spring 29, so as to maintain the bell crank 19 and the valve rod in either extreme position, through the instrumentality of the link 25.

In order to cushion the movements of the valve rod 18, and make the operation as noiseless as possible, I provide cushion members, preferably in the form of rubber buffers, arranged in path of travel of the valve rod. To this end, the ends of the valve housing are provided with sheet metal heads which are bent to form sockets 34, which receive and hold frictionally the blocks 35 of rubber or other similar resilient material. The buffers 35 are located at opposite ends of the valve housing 8, and in the path of the ends 36 of the valve rod, and as the valve rod reaches either one of its extreme positions, it contacts with one of the rubber buffers 35 and is thereby stopped with a quiet cushioning action.

For the purpose of supporting the receptacle, I provide a plurality of plates 30, each of which is fixed to the bottom, preferably by soldering or in some other convenient manner, and adapted to receive an adjustable leg. To this end, each plate 30 is bent upon itself at each end 31 to afford a leg receiving socket. The leg is preferably formed of wire bent upon itself to afford a toe portion 32, and substantially parallel supporting portions or arms 33, which slid-

ably and frictionally engage the sockets 60 formed by the ends 31 of the plate 30.

I claim:

1. The combination with a receptacle, of an agitating device, a carrier for the agitating device, a fluid motor arranged within the receptacle for actuating said agitating device, and a jacket surrounding said motor and spaced therefrom to afford an insulating space.

2. The combination with a receptacle, of an agitating device, a carrier for the agitating device, a fluid motor supported on the bottom of the receptacle for actuating said agitating device, and a jacket surrounding said motor in spaced relation thereto, said jacket having an opening at its top and an opening at the bottom leading to the outside of the receptacle.

3. The combination with a receptacle, of an agitating device movable within the receptacle, a fluid motor arranged within the receptacle and operatively connected with said agitating device, and means surrounding the motor for insulating the water within the receptacle against the effect of the temperature of the fluid in the motor.

4. The combination with a receptacle, of a carrier, means for reciprocating the carrier, a reciprocatory sleeve having a cam way, a stationary abutment engaging said cam way and causing turning of the sleeve, a friction washer interposed between the sleeve and carrier, and friction surfaces on the sleeve and carrier cooperating with said washer.

5. The combination with a receptacle, of a carrier, a piston mounted on the carrier, a cylinder in which said piston reciprocates, an oscillatory sleeve, a friction washer between said sleeve and said piston, and friction surfaces on the piston and sleeve cooperating with said washer.

6. The combination with a receptacle, of a carrier, means for reciprocating the carrier, a reciprocating sleeve, means for oscillating said sleeve, and a friction washer interposed between the sleeve and carrier.

7. In mechanism of the class described, a receptacle, an agitator and means for reciprocating said agitator vertically within the receptacle; relatively movable devices having friction surfaces adapted to yieldably rotate said agitator intermittently, said devices being rendered effective by the reciprocation of said agitator.

In witness whereof, I have hereunto signed my name.

FRANK A. ADAMS.
